CORK SIFTER

John D. Elder, Catonsville, Md., assignor to
 Crown Cork & Seal Company, Inc., New York,
 N. Y., a corporation of New York

Application May 6, 1929. Serial No. 360,670

9 Claims. (Cl. 209—366)

My invention relates to cork sifters, and more particularly to a mechanism which may be effectively utilized for the separation of cork granules or particles varying in dimension, and the delivery of the granules or particles of different sizes to independent collection points.

Cork particles, both because of their size and because of the low specific gravity of cork wood, during a sifting operation develop very little inertia, either static or moving. As a consequence, it is essential, in such sifters, to impart high speed to the screens with a short quick change of direction in the movements thereof, in order to ensure the necessary violent agitation and movement of the cork particles to effectively separate the smaller particles from the mass delivered to the screen. The high speed at which the screens are required to be operated, not only tends towards a severe racking of these screens, but a loss of efficiency in the event of the development of looseness in the frame of the screens.

With the above conditions in mind, I have provided a cork sifter which is so constructed as to permit the actuation of the screens at high speeds, such screens being so supported and controlled in their movements as to relieve them from stresses which would tend to rack the frames of the screens. This permits the screens to be made of light material and still have them possess sufficient strength to withstand the severe wear to which they are necessarily subjected with a prolonged use of the structure.

In addition to the structural characteristics above referred to, a cork sifter embodying my invention is so constructed that the cork particles upon the screen will be subjected to a continuing violent agitation which, by reason of the structure of the screens, will cause the bulk of the matter delivered thereto, to travel the entire length of the screen, and be delivered to one receptacle, and the matter progressively rejected as a result of the screening operation, to be delivered to a separate receptacle.

A sifter embodying the invention is particularly adaptable to the grading of granular cork for use in the production of composition cork. In the production of such cork, it is desirable, in the interests of uniformity in the product, that the cork granules used, be of graded sizes, and that the volume of the granules of each size be fairly accurately proportioned in a batch of the cork composition, in order to secure a highly resilient product free from voids.

The granulation of cork results in a variable product ranging from fairly large particles of

cork to a substantially impalpable cork dust and fine grit. This condition results in part from the functioning of the granulating machine, and in part from the age and character of the cork wood passed through this machine.

The dust and grit are valuable in the production of composition cork, and some of the smaller granules must be used sparingly.

In a sifter embodying my invention, a succession of superimposed screen units operated from the same source of power may be effectively used. These various units are so constructed that the particles rejected by the screen of one unit will be delivered to the screen immediately below, in a manner to progressively remove from the mass of granular cork delivered to the sifter, the usable cork granules graded to size, the various gradings being substantially free from dust, grit and smaller particles of the granular cork. The usable cork may thus be segregated from the dust and grit, which are not usable, the latter being automatically discharged by the machine.

The various screen units are each supported by strong rigid thrust members closely adjacent the actuating mechanism for the unit, these members being so constructed as to effectively brace the screen about the corners thereof; thus avoiding racking of the frame of the screen as a result of the thrust thereon by the actuating means.

The actuating means itself is so constructed and arranged that the movement of the screen results entirely from a properly timed movement of the different thrust members against the frame, there being no pulling action upon this frame. The manner of actuating the screen is such that the frame is subjected to the minimum of stress from the actuating means, thus permitting the structure of the screens to be light, it being possible to make these frames of wood. The use of a screen unit having very little weight permits the operation of a multiple unit sifter at high speeds with low power.

The escape of dust about the sifter is not great, but the construction of the actuating means is such as not to be interfered with, in the event of the settling of dust thereon.

Preferably, the collection receptacles consist of ordinary bags, which form no part of the invention, the sifter being provided with ducts communicating with the offtake chutes of the various screen units and provided with a distending member adjacent the outlets thereof about which the bags may be connected.

The invention consists primarily in a cork sifter embodying therein a plurality of superimposed units, each embodying a frame, having therein a screen, an imperforate bottom plate beneath said screen and spaced therefrom, and discharge means communicating respectively with the space above said screen and above said imperforate bottom plate the discharge means communicating with the space above said imperforate bottom plate delivering the screened material to the unit below, a plurality of thrust members operatively engaging diametrically opposite corners of each of said frames, supporting means for said frames carried by said thrust members respectively, a fixed bracket adjacent each of said thrust members, co-operating bearings carried by said thrust members and said brackets respectively, a rotatable member mounted upon each of said brackets, operative connections between said rotatable member and the thrust member associated therewith, and means common to the rotatable members associated with each unit for imparting similar, simultaneous movement thereto; and in such other novel features of construction and combination of parts, as are hereinafter set forth and described, and more particularly pointed out in the claims hereto appended.

Referring to the drawings,

Fig. 1 is a front elevation of a cork sifter embodying the invention, with portions of the main frame broken away;

Fig. 2 is a side view thereof with portions of the main frame broken away;

Fig. 3 is a plan view thereof with portions of the feed hopper, the mesh of the uppermost screen and a portion of the top frame broken away;

Fig. 4 is an enlarged detail view, partly in elevation and partly in section, of one of the elements in the actuating mechanism;

Fig. 5 is a plan view thereof;

Fig. 6 is a plan view of one of the screen units;

Fig. 7 is an enlarged sectional view of said unit, and

Fig. 8 is an enlarged sectional view on the line 7—7 of Fig. 6.

Like numerals refer to like parts throughout the several views.

In the embodiment of the invention shown in the drawings, the structure is such as to be particularly adapted for the screening and grading of granular cork. The structure therein shown embodies a main frame 10, having mounted thereon a plurality of superimposed screen units 11, 12, 13, 14 and 15. Each of these units 11 to 15 inclusive may have the same general construction as each of the other units.

The actuating means for all of the units is derived from a single source of power so that, notwithstanding that a plurality of thrust members are operative upon each unit, the application of power through such members is so timed as to each, as to ensure their proper coordination in securing the desired movements of the screen unit.

I will first describe one of the screen units in detail, and then explain the mechanisms for imparting movement to this screen unit and to the various other screen units.

Referring more particularly to the screen unit 11, which is of the same construction as the units 12, 13, 14 and 15, it consists of a wooden frame having side bars 16 and 17, a front bar 18 and a back bar 19, these various bars all being of wood, suitably glued or otherwise secured together.

The side bars 16 and 17 are each provided with a cleat 20, and the back bar 19 with a cleat 21, for supporting a frame 22 carrying a wire mesh 23 of the desired gauge. The gauge of the mesh 23 will vary with the character of the material to be screened or graded.

The cleats 20 extend upon an incline from adjacent the front bar 18 to adjacent the back bar 19 so as to pitch the screen 23 toward said front bar, which has an outlet opening 24 extending therethrough.

Also secured to the side and front bars of the screen unit, is an imperforate bottom plate 25, positioned below the screen mesh 23, but pitched in the reverse direction to said mesh. This plate 25 is preferably of sheet metal having a turned edge, by means of which it may be fitted and secured to the bars 16, 17 and 18.

The plate 25 is unconnected with, and spaced away from, the back bar 19, affording space for a rectangular collecting and delivering hopper 26, the discharge nozzle 27 of which is of less length than the width of the screen frame so as to be positioned well away from the corners of said frame. The reason for this is that the actuating power for imparting movement to the screen unit is applied at the corners, and clearance is required about the corners for permitting the assembly of the thrust members in relation to the frame, and the movements of said members and said frame in relation to the parts co-operating with said members.

Cutout sections of the back and side bars are shown at 28 and 29 in Fig. 7, and cutout portions of the front and side bars are shown at 30 in said Fig. 7.

The location of the hopper 26 is closely adjacent the point of delivery of the granular or other material to the screen 23, at which point the volume of material rejected by the screen will be the greatest. This will appear more fully hereinafter.

The frame of the screen unit is of progressively increasing depth from adjacent the front bar 18 to adjacent the back bar 19, so as to afford adequate capacity above the mesh 23 and between this mesh and the bottom plate 25.

The hopper 26 has side walls 31 and 32 and a rear wall 33 adjacent the bar 19 which converge toward the discharge nozzle 27, the side of the hopper towards the front bar 18 being open, except for side wings 34 closing the gap between the converging side walls 31 and 32 and the side bars 15 and 16. By this construction, the bottom plate 25 discharges directly into the discharge nozzle 27.

Suitable corner fillets may be used where required to strengthen the screen unit at the corners.

Leading from the opening 24 through the front bar 18, is a closed chute 35 having converging end walls 35a and 35b and the movable section of a discharge conduit 36 leading from the bottom of this chute.

The chute extends downwardly at an angle so as to ensure a rapid conveyance of the particles from above the screen, the bottom of the opening 24 being substantially flush with the top of the screen. The degree of angularity of the end walls 35a—35b of the chutes of the different units varies in order to differently locate the discharge conduits 36 and thus permit the more convenient locating of the collection receptacles, the bags 37.

The movable portions 36a of the conduits 36

are connected with the fixed sections of said conduits by a flexible conduit section 38, so as to confine the particles flowing from the one conduit section to the other and yet permit the free movement of the screen units during the sifting operation. Each of the conduits 36 is provided adjacent its outlet with an enlarged head 39, about which the tops of the bags may be partially closed, these enlarged heads serving to distend 16 the tops of the bags so as to avoid possible clogging of the chutes toward the mouths of said bags.

By making the ducts of a plurality of sections 36-36a, one of each of which sections is fixed, 15 and the other of which is movable with a screen unit, the difficulties of collecting the graded matter is obviated and the free movement of each sifter unit is permitted. The flexible connecting sections 38 are desirable, since it prevents the 20 possibility of draughts picking up the small, light particles of cork and blowing them about the room. Other means for securing this result, however, may be employed.

All of the parts of the screen unit heretofore 25 described are of wood, excepting the mesh 23, the bottom plate 25, the hopper 26 and its outlet 27, and the chutes 35 and the movable portion of the conduit 36, which are of metal.

Operative upon each corner of the screen 30 frame is a thrust member having the two-fold function of imparting movement to the screen and so supporting the corners thereof, while movement is being imparted thereto, as to prevent any possible racking of the frame.

35 Each of these thrust members is identical in construction with every other, so that a detailed description of but one of them is necessary.

This thrust member comprises a metal casting having contact plates 40 and 41 extending from 40 each other with a 90° angle, so that when positioned in relation to the frame, one of the plates, as 40, will engage either the front or back bar 18 or 19 of the frame, and the other plate, as 41, will engage a side bar 16 or 17 of the frame. 45 Projecting from the angle of these plates 40 and 41 is a seat 42 adapted to fit a cutout portion 28 or 30 and receive and support the edge of the front and side bars of the frame at the corner, in connection with which the thrust member is used. The seat 42 is recessed as shown, to provide a suitable housing for a downwardly presented anti-friction bearing member 43.

Adjacent each of the thrust members co-operating with each unit is a bracket 44 secured to 50 the main frame 10. This bracket is provided with a bearing 45 with which the anti-friction bearing member 43 of the thrust members co- 55 operates.

The bearing member 45 serves to support the 60 adjacent thrust member, and therethrough, one corner of the screen unit, while at the same time permitting free movement of said unit.

65 Mounted in a suitable bearing in the bracket 44 is a rotatable member, as the gear 46, carrying a crank pin 47, located at a short radius of said gear, and engaging a bearing 48 in an arm 49 forming a part of the thrust member. The cutout portions 29 are provided to afford proper clearance between the frame of the unit and the bearing 45.

70 In the embodiment of the invention shown in the accompanying drawings, each of the brackets 44 co-operating with a thrust member of each unit is in vertical alinement with a bracket co-operating with each of the other superimposed

screen units, and the gears 46 carried by each set of vertically alined brackets have their axes in vertical alinement. Consequently, there are four sets of vertically alined gears 46, the gears of each set receiving power through the same shaft, and the shafts co-operating with all of the sets of vertically alined gears being driven through a mechanism receiving its power from a single source. This ensures absolute accuracy in the timing, not only of the operation of all of the gears 46 operative upon each unit, but of all of the other gears operative upon the other units.

75 It is essential that the crank pins 47, upon the gears 46 operative upon the thrust members co-operating with any unit, be set upon the same radius, and that all of the thrust members shall have the same movement. The crank pins 47 of one unit may be set upon a different radius from the crank pins of another unit, but all of the crank pins of each unit, as stated, must be set the same. This relieves the frame of the screen unit from substantially all strains due to the application of power thereto by the actuating means therefor.

80 The power shafts actuating the gears 46 of each set are shown at 50, 51, 52 and 53, the shaft 50 being provided with gears 54, the shaft 51 being provided with gears 55, the shaft 52 being provided with gears 56 and the shaft 53 being 85 provided with gears 57. The gears 54, 55, 56 and 57 respectively mesh with a gear 46.

85 Each of the shafts 50 to 53 carries a bevel gear, these gears being shown at 58, 59, 60 and 61. The gears 58 and 59 are enmeshed with bevel gears 62 and 63 carried by a shaft 64. The gears 60 and 61 are enmeshed with gears 65 and 66 carried by a shaft 67. The shafts 64 and 67 each carry a bevel gear 68-69, which in turn are enmeshed with bevel gears 70 and 71 upon a main power 90 shaft 72, which may be driven from any desired source of power, not shown.

95 The shaft 72 is driven at a speed to impart a high speed of rotation to the various gears 46. Good results have been secured by actuating the 100 screen units at the rate of four hundred or more cycles per minute.

105 Discharging into the uppermost screen unit 11 is a feed hopper 73, having an outlet 74 of a width which will permit a free movement of the screen 11. This hopper continuously discharges cork granules or particles upon the mesh 23 of the screen unit 11 adjacent the back bar 19 of the frame of this unit.

110 The lowermost screen unit 15 is provided with an offtake pipe 75 through which dust and grit may be withdrawn in any desired manner, as by a suitable suction device. This pipe 75 is the only outlet for the collecting and discharging 115 hopper of this unit.

120 The lay-out of the gearing above described is such that the gears 46 all rotate in the same direction and at the same speed. The gearing arrangement is shown in the drawings, and need 125 therefore not be described in detail.

130 The operation of the herein described cork sifter is substantially as follows:—

135 In assembling the sifter of the invention, the various actuating and thrust members are first completely assembled in relation to the main 140 frame 10 and each other, and the screen unit frames are merely fitted to the various thrust members without being connected therewith.

145 It will be noted that the discharge 74 of the hopper 73 is adjacent the back bar 19 of the 150

uppermost screen unit 11, slightly forwardly of the hopper 26. An adequate supply of granular or other material is stored in the hopper 73, this material being free to gravitate through the outlet 74 until this outlet is clogged by the accumulation of the material upon the screen 23 of the unit 11. In this manner the supply of granular or other material delivered to this screen is controlled by the screening action, the delivery of 10 this material being continuous as required.

When power is applied to the shaft 72, all of the shafts 50, 51, 52 and 53 and the gears 46 carried thereby respectively are simultaneously rotated at the same speed and in the same direction.

The resultant short circular movement of the screen causes a violent agitation of the granular or other matter upon the screen proper 23, so that the smaller particles fall through the mesh of 15 the screen and the larger particles remain thereon.

The inclination of the mesh 23 will cause the light cork particles to gradually work toward the discharge outlet 24, there being no tendency of 20 this matter to move by gravity along the screen. The bulk of the rejected matter will pass through the screen close to the point of discharge of the bulk of the matter upon the mesh, although with the high speed of operation of the machine, there 25 will be a progressive separation of the different sizes throughout substantially the entire area of the screen, although its dimensions are such that by the time that the larger particles reach the discharge outlet 24, all of the finer matter will 30 have passed through the screen.

The rejected granules or particles will fall upon the bottom plate 25, and the inclination of this plate will cause them to move toward the hopper 26, through the outlet 27 of which they will descend upon the mesh of the unit below in substantially the same manner as the granular mass is discharged upon the screen of the uppermost unit 11. There is a tendency of the matter delivered upon the bottom plate to collect and accumulate upon the bottom plate adjacent the discharge hopper, but the increased capacity of 45 the chamber between same and the wire mesh permits this without clogging the machine.

This condition is repeated throughout the succeeding lower units until ultimately the smallest 50 usable particles are separated from the dust and grit, and the latter are discharged through the outlet 74 of the lowermost unit.

The graded granules or particles, passing 55 through the discharge opening 24 of a unit, will slide along the bottom of the discharge chute 35 of that unit and pass by gravity through the conduit portion 36 movable with said chute, the flexible conduit portion 38 and the fixed conduit 60 portion 36a to the collecting receptacle 37. The flexible conduit section 38 is to permit the free movement of the movable conduit section 36 with the discharge chute and the sifter unit while directing the particles to the fixed conduit sections 65 36a and preventing the escape of such particles, either as a result of air currents, or as a result of the impetus given to some of these particles as a result of the rapid movements of the movable conduit section 36.

70 With this rotation of said gears 46, the thrust members actuated thereby respectively will each be actuated to impart or permit both longitudinal and lateral movement to the screen unit with which they co-operate. The operation of each 75 member will differ from that of every other mem-

ber, and there will be not only a reversal in the direction of movement of the screen unit during each revolution of the gear, but there will be a constantly changing longitudinal and lateral speed of the unit.

For convenience of description, the complete cycle of operations will be divided into four stages, each requiring 90° of movement of the cranks 47 carried by the gears 46.

During the first stage, the thrust member actuated from the shaft 50 will be actuated to advance the contact plate 40 thereof to impart a longitudinal thrust to said unit, and the contact plate 41 to impart a lateral thrust thereto. There will be a progressively increasing speed in the 85 longitudinal movement of the unit during this stage, and a progressively decreasing speed in its lateral movement.

During this stage, the thrust member actuated from the shaft 51 will be so actuated as to cause 95 the contact plate 40 thereof to recede with the same speed variations as are present in the longitudinal movement of the screen unit, and the contact plate 41 to advance and impart lateral movement to the screen with the same speed 100 variations therein as result from the movements of the thrust member actuated from the shaft 50.

The thrust member actuated from the shaft 52, during this stage, will be actuated so as to advance the contact plate 40 carried thereby to impart 105 part longitudinal movement to the screen in the same manner as the contact plate 40 of the thrust member actuated from the shaft 50. The contact plate 41 of this thrust member, however, will recede laterally so as to permit lateral movement 110 of the screen unit.

The thrust member actuated from the shaft 53 will be actuated so as to cause both plates 40 and 41 thereof to merely recede longitudinally and laterally from the screen unit, and permit 115 both longitudinal and lateral movement thereof.

The movement of each of the thrust members is the same as that of every other, so that during this movement of the screen unit, and in fact of other movements thereof, it will be supported 120 by, and firmly held between, the various thrust units. The contact plates 40 and 41 of each thrust member, as stated, will reinforce the frame of the screen unit about the point of the application of power thereto by said thrust members.

During the second stage of the cycle, the plates 40 of the thrust member actuated from the shaft 50 will continue to advance and impart longitudinal movement to the screen unit, and the plate 40 of the thrust member actuated from the 130 shaft 51 will continue to recede, both plates 40 having a progressively decreasing rate of speed. The plates 41 of both of these members, however, will recede and cease to impart any lateral movement to the screen unit. The plate 40 of 135 the thrust member actuated from the shaft 52 will continue to advance in the same manner as the plate 40 of the member actuated from the shaft 50, and the plate 40 actuated from the shaft 53 will continue to recede in the same manner 140 as the plate 40 actuated from the shaft 51. The plates 41, however, of the thrust members actuated from both the shafts 52 and 53 will advance with a progressively increasing speed, thus reversing the lateral movement of the screen 145 unit.

During the third stage, the longitudinal direction of movement of the screen unit will be reversed, but the lateral movement will continue throughout this stage the same as during the 150

second stage. During this stage, the thrust member actuated from the shaft 53 will have the same operative effect as the thrust member actuated by the shaft 50 during the first stage, and the

5 thrust member actuated from the shaft 51 will have the same operative effect as the thrust member actuated from the shaft 52 during the first stage. The thrust members actuated by the shafts 50 and 52 will have the same operative

10 effects as the thrust members actuated by the shafts 53 and 51 respectively during the first stage.

During the fourth or final stage of the cycle, the longitudinal movement of the screen unit will continue as during the third stage, but the lateral movement will be reversed. During this stage, the operations of the thrust member actuated from the shaft 53 will be the same as the operations of the thrust member actuated from the shaft 50 during the second stage, and vice versa, 15 and the operations of the thrust member actuated from the shaft 51 will be the same as those of the thrust member actuated from the shaft 52 during the second stage, and vice versa.

20 The terms "advance" and "recede", as herein used, refer to the movements of the contact plates 40 or 41 in relation to the position of the screen at the moment.

25 The above operation is described at considerable length merely to emphasize the action of the various thrust members in relation to the frame of the screen unit. It will be noted that there is a constant shifting of the point of application of power to this frame, and that the arrangement of the contact plates 40 and 41 is such as to impart rigidity not only to the portion of the frame against which the thrust occurs, but upon both sides of the angle adjacent thereto.

30 The actuation of each of the superimposed screen units will be the same as that above described, although by changing the location of the crank pin 47 upon any gear 46, the timing in the reversal in the direction of movement, and the changes of the speed of movement may be varied as to the different units. This, however, is merely a matter of choice and not essential to the machine.

35 The advancing and receding of the different thrust members in the manner described, not only imparts movement to the screen unit, but avoids any resistance of any part of the actuating mechanism to this movement. Furthermore, the moving inertia of the screen unit is so controlled by the thrust members that the frequent reversal of the direction of movement of the screen unit 40 cannot result in the development of any looseness of parts and racking of this structure.

45 It is obvious that the various sizes of usable material are completely segregated, by providing separate receptacles into which the output of the machine as a whole is delivered.

50 While I have referred to the dust and grit or other matter discharged from the lowermost unit as being not usable, this refers merely to the purposes for which the matter delivered to the receptacles 37 is to be used. This matter discharged from the lowermost unit 15 is merely waste as to one product, but may be used for other purposes.

55 It is not my intention to limit the invention to the precise details of construction shown in the drawings, it being apparent that such may be varied without departing from the spirit and scope of the invention.

60 Having described the invention, what I claim

as new and desire to have protected by Letters Patent, is:—

1. A cork sifter embodying therein the combination with a sifter unit, comprising a rectangular frame having therein a screen, an imperforate bottom plate beneath said screen and spaced therefrom, and discharge means communicating respectively with the space above said screen and above said imperforate bottom plate, of a thrust member adjacent each corner of said frame including therein contact plates extending from each other at an angle to engage said frame about the corner thereof, a seat within the angle of said plates supporting said frame, a fixed bracket adjacent each of said thrust members, co-operating bearings carried by said thrust members and said brackets respectively, a rotatable member mounted upon each of said brackets, operative connections between said rotatable member and the thrust member associated therewith, and means common to the rotatable members associated with said unit for imparting similar, simultaneous movement thereto.

2. A cork sifter embodying therein the combination with a sifter unit, comprising a frame having front, back and side bars, a screen supported within said frame, said screen being pitched toward said front bar, said front bar having an opening therethrough above said screen, a discharge chute communicating with said opening, an offtake duct comprising a section carried by and movable with said chute, and a fixed section, an imperforate bottom plate carried by said frame beneath said screen and spaced therefrom, and discharge means communicating with the space above said imperforate bottom plate, of a plurality of thrust members operatively engaging the base of said frame, supporting means for said frame carried by said thrust members respectively, a fixed bracket adjacent each of said thrust members, co-operating bearings carried by said thrust members and said brackets respectively, a rotatable member mounted upon each of said brackets, operative connections between said rotatable member and the thrust member associated therewith, and means common to the rotatable members associated with said unit for imparting similar, simultaneous movement thereto.

3. A cork sifter embodying therein the combination with a sifter unit, comprising a frame having front, back and side bars, a screen supported within said frame, said screen being pitched toward said front bar, said front bar having an opening therethrough above said screen, a discharge chute communicating with said opening, an offtake duct comprising a section carried by and movable with said chute, a fixed section, and a flexible section connecting said other conduit sections, an imperforate bottom plate carried by said frame beneath said screen and spaced therefrom, and discharge means communicating with the space above said imperforate bottom plate, of a plurality of thrust members operatively engaging the base of said frame, supporting means for said frame carried by said thrust members respectively, a fixed bracket adjacent each of said thrust members, co-operating bearings carried by said thrust members and said brackets respectively, a rotatable member mounted upon each of said brackets, operative connections between said rotatable member and the thrust member associated therewith, and means common to the rotatable mem-

bers associated with said unit for imparting similar, simultaneous movement thereto.

4. A cork sifter embodying therein the combination with a sifter unit, comprising a frame having front, back and side bars, a screen supported within said frame, said screen being pitched toward said front bar, said front bar having an opening therethrough above said screen, a discharge chute communicating with said opening, an offtake duct comprising a section carried by and movable with said chute, and a fixed section, an imperforate bottom plate carried by said frame beneath said screen and spaced therefrom, said bottom plate being spaced away from said back bar of said frame, a collecting and delivering hopper having a downwardly presented discharge nozzle positioned within the space between said bottom plate and said back bar, of a plurality of thrust members operatively engaging said frame, supporting means for said frame carried by said thrust members respectively, a fixed bracket adjacent each of said thrust members, co-operating bearings carried by said thrust members and said brackets respectively, a rotatable member mounted upon each of said brackets, operative connections between said rotatable member and the thrust member associated therewith, and means common to the rotatable members associated with said unit for imparting similar, simultaneous movement thereto.

5. A cork sifter embodying therein the combination with a sifter unit, comprising a rectangular frame having therein a screen, an imperforate bottom plate beneath said screen and spaced therefrom, and discharge means communicating respectively with the space above said screen and above said imperforate bottom plate, of a thrust member adjacent each corner of said frame including therein contact plates extending from each other at an angle to engage said frame about the corner thereof, a seat within the angle of said plates supporting said frame, a downwardly presented bearing carried by said seat, a fixed bracket adjacent each of said thrust members, said bracket having a bearing co-operating with the bearing upon said support, a gear rotatably mounted upon said bracket, a crank pin upon said gear, an arm bearing upon said crank pin carried by said thrust member, and means common to the gears carried by the brackets associated with said unit for imparting similar, simultaneous movement to said gears, said crank pins being set upon the same radius of each of said gears.

6. A cork sifter embodying therein a sifter unit having a rectangular frame, thrust members operatively engaging diametrically opposite corners of said frame, supporting means for said frame carried by said thrust members respectively, a fixed bracket adjacent each of said thrust members, co-operating bearing members carried by said thrust members and said brackets respectively, a rotatable member mounted upon each

of said brackets, operative connections between said rotatable member and the thrust member associated therewith, and means common to the rotatable members associated with each unit for imparting similar, simultaneous movement thereto.

7. A cork sifter embodying therein a sifter unit having a rectangular frame, a thrust member adjacent each corner of said frame including therein contact plates extending from each other at an angle to engage said frame about the corner thereof, a seat within the angle of said plates supporting said frame, a fixed bracket adjacent each of said thrust members, co-operating bearings carried by said thrust members and said brackets respectively, a rotatable member mounted upon each of said brackets, operative connections between said rotatable member and the thrust member associated therewith, and means common to the rotatable members associated with said unit for imparting similar, simultaneous movement thereto.

8. A cork sifter embodying therein a sifter unit having a rectangular frame, a thrust member adjacent each corner of said frame including therein contact plates extending from each other at an angle to engage said frame about the corner thereof, a seat within the angle of said plates supporting said frame, a downwardly presented bearing carried by said seat, a fixed bracket adjacent each of said thrust members, said bracket having a bearing co-operating with the bearing upon said support, a gear rotatably mounted upon said bracket, a crank pin upon said gear, an arm bearing upon said crank pin carried by said thrust member, and means common to the gears carried by the brackets associated with said unit for imparting similar, simultaneous movement to said gears, said crank pins being set upon the same radius of each of said gears.

9. A cork sifter embodying therein a sifter unit having a rectangular frame, a thrust member adjacent each corner of said frame, including therein contact plates extending from each other at an angle to engage said frame about the corner thereof, a seat within the angle of the plates of each thrust member supporting said frame, a downwardly presented bearing carried by said seat, a fixed bracket adjacent each of said thrust members, each bracket having a bearing co-operating with the bearing upon said support, a gear rotatably mounted upon each bracket, a crank pin upon said gear, an arm bearing upon said crank pin carried by the co-operating thrust member, said gears being arranged in four sets having their axes vertically aligned, vertical shafts carrying the gears of each set, and means simultaneously driving all of said shafts so as to rotate all of said gears in the same direction and at the same speed, said crank pins co-operating with each unit being set upon the same radius of each of the gears carrying same.

JOHN D. ELDER.
